United States Patent Office

Des. 205,806
Patented Sept. 20, 1966

205,806

REPRODUCTION MACHINE

Robert G. Plantholt, Rochester, Mich., assignor to Xerox
Corporation, Rochester, N.Y., a corporation of New
York

Filed Sept. 30, 1965, Ser. No. 87,243

Term of patent 14 years

(Cl. D61—1)

Des. 205,806

PAGE 2

FIG. 2

FIG. 3

FIG. 4

FIG. 5

FIG. 1 is a right-hand front and top perspective view of a reproduction machine, showing my new design;

FIG. 2 is a top view thereof;

FIG. 3 is a front elevational view thereof;

FIG. 4 is a left side elevational view thereof; and

FIG. 5 is a rear elevational view thereof.

I claim:

The ornamental design for a reproduction machine, as shown.
